Primary Examiner—Nelson C. Holtje**[57] CLAIM**

The ornamental design for a combined clock and air freshner, as shown and described.

DESCRIPTION

FIG. 1 is a front elevational view of the combined clock and air freshner of the present invention;

FIG. 2 is a rear elevational view of the combined clock and air freshner of FIG. 1;

FIG. 3 is a left side elevational view of the combined clock and air freshner of FIG. 1, the right view being a mirror image thereof;

FIG. 4 is a top plan view of the combined clock and air freshner of FIG. 1; and,

FIG. 5 is a bottom plan view of the combined clock and air freshner of FIG. 1.

The broken lines showing of a clock “hands” in FIG. 1 is for illustrative purposes only and form no part of the claimed design.
